SIGNAL CODE AND PROGRAM SENDING
SYSTEM

John H. Wheelock, Fitzwilliam, N. H., assignor to
Signal Engineering & Manufacturing Com-
pany, New York, N. Y., a corporation of Massa-
chusetts

Application August 21, 1939, Serial No. 291,191

8 Claims. (Cl. 177—360)

The present invention relates to a signal code and program impulse transmitting system for controlling the operation of suitable devices for sounding or displaying signals at different locations throughout a building, or other establishment in which the system is installed. Calling and locating individuals by code number and the transmission of so-called program signals, to indicate time, or the existence of an emergency, are well known uses of such a dual system.

The object of the invention is to provide a fully automatic signal system of the above indicated character, that is adapted to transmit either a predetermined number of rounds of code sequences, as for locating individuals, under the control of a code determining device, or a given series of evenly spaced program impulses readily distinguishable from any of the code signal sequences, under the control of an auxiliary device, such as a time clock, or similar device. According to the present invention, the improved system is not only capable of selectively transmitting code impulses or program impulses, but also provides means for automatically preventing any possible interference between the code and program impulses, as well as for assuring successive transmission of complete sequences of either code or program impulses, entirely irrespective of whether the code determining device is operated before the program control contacts, or vice versa.

By reason of the circuits automatically established in the improved system, any one of the following operations may take place:

(a) Transmission of code sequences for a predetermined number of rounds, in response to operation of a code determining member, such as a key.

(b) Transmission of a predetermined number of program impulses, in response to operation of the program controlling contacts, as operated by a clock, or similar device.

(c) Transmission of a predetermined number of complete rounds of code sequences, in response to actuation of a key, as in (a), automatically followed by transmission of a predetermined number of program impulses, in response to closure of the program contacts at any time during the transmission of code sequences.

(d) Transmission of a predetermined number of program impulses, in response to functioning of the program contacts, as in (b), automatically followed by transmission of a predetermined number of complete rounds of code sequences, in response to actuation of a code determining key

at any time during the transmission of program impulses.

Summarizing the above noted modes of operation, it is apparent that the entire system works on an automatically non-interfering and succession operation basis, irrespective of whether a code key or the program device operates first, to the end that a complete cycle of code sequences will be followed by a complete round of program impulses, or vice versa. The four modes of operation summarized above, will next be described with reference to the accompanying drawings, in which:

Fig. 1 is a diagrammatic view, illustrating the system in its normal non-operating condition.

Fig. 2 illustrates the system of Fig. 1, operating to transmit a code sequence.

Fig. 3 illustrates the system of Fig. 1, operating to transmit program impulses.

Fig. 4 illustrates the system of Fig. 2, in condition to automatically follow the transmission of code impulses by the transmission of program impulses.

Fig. 5 illustrates a portion of the system of Fig. 2, in condition to automatically follow the transmission of program impulses by the transmission of code impulses.

Fig. 6 is a fragmentary view, illustrating a portion of the parts of Fig. 5 in different positions.

Fig. 7 is a fragmentary view, showing the mechanical relation between certain parts of the system.

Figs. 8 to 11 inclusive are fragmentary views illustrating parts of the code setting device in different positions.

Referring first to Fig. 1, the system includes a code determining device of any suitable type, which is shown, for purposes of illustration, as comprising a key K operable to set up different code combinations, with respect to associated contacts $k-1$, $k-2$, $k-3$, etc. The key-actuated contacts $k-1$, $k-2$, $k-3$, etc. are connected to correspondingly designated contacts $c-1$, $c-2$, etc. of a commutating device C. The contacts $c-1$, $c-2$, etc. are in the form of projections spaced around the periphery of a ring 1, but insulated from each other, and an arm 2 mounted on a shaft 3 passing through the ring, is adapted to successively bear on the contacts $c-1$, $c-2$, etc.

A motor M serves to drive the shaft 3 which carries a second arm 4, adapted to bear successively on a series of contacts 5 mounted on a ring 6 parallel to the ring 1, with the contacts 5 formed and arranged identically with contacts

c-1, c-2, etc. and all connected to the ring 6. The arms 2 and 4 are connected together so as to turn in unison with the shaft 3, as shown in Fig. 7, with both arms being insulated from the shaft 3, and being equally flexed to maintain uniform contact pressure as they pass over the projections on the rings 1 and 6. The ring 6 is connected by conductor 7 to one of a pair of spaced master contacts 8, adapted to be bridged by a member 9 mounted on a pivoted arm 10.

The arm 10 provides an extension 10a bearing on a disk 11, also mounted on the shaft 3. The disk 11 provides a series of projections 12, having the same form as the contacts 5 on ring 6, and the contacts *c-1, c-2, etc.* on ring 1, although spanning a smaller angle than the ring contacts, measured in either direction of rotation of the shaft 3. As a result of this angular relation between projections 12 and the ring contacts, the circuit between the master contacts 8 is made and broken by the bridging member 9, while the arms 2 and 4 are successively in engagement with the contacts *c-1, c-2, etc.* and contacts 5, whereby all arcing is restricted to the master contacts 8 during operation of the commutating device C.

The motor driven shaft 3 is connected to a control shaft 13 through reduction gearing 14, so that the shaft 13 makes a predetermined number of revolutions, three, as shown, for each revolution of the shaft 3. The shaft 13 carries a program disk 15, provided around its periphery with a series of projections 16 that are closer together than are the projections 12 on the master contactor disk 11, for a purpose which will hereinafter appear. An arm 17 pivoted at 17a, bears on the program disk 15, so that rotation thereof is adapted to impart an oscillatory movement to the arm 17, to carry a contact 18 rapidly into and out of engagement with a stationary contact 19. The shaft 13 also carries a motor control cam 20, providing a notch 21 in its periphery, in which is normally received the free end of an arm 22 pivoted at 22a. An extension of the arm 22 carries an insulated contact 23, which is maintained out of engagement with a stationary contact 24, as long as the end of the arm 22 remains in the cam notch 21.

One terminal of the motor M is permanently connected to a supply main S, suitably energized from a source of power, not shown, while the other motor terminal is connected by a conductor 25 to the contact 23 mounted on the arm 22, under control of the cam 20. The stationary contact 24 is connected by a conductor 26 to a second supply main S', energized from the same source as the main S. Therefore, closure of the contacts 23 and 24 by the control cam 20, is adapted to establish and maintain an energizing circuit for the motor M that will be broken once for each complete revolution of the cam 20, or three revolutions of the motor shaft 3.

A starting contact 27 is connected to the conductor 25 between the motor terminal and contact 23, and this contact 27 is adapted to be momentarily engaged by the key K when the latter is pressed all the way in, as indicated in dotted lines, to initiate the transmission of code sequences. The key contact *k-1* is connected by a conductor 28 to a stationary contact 29 that is normally engaged by a movable arm 30, forming part of a program relay, generally designated by the reference character P. The relay arm 30 is connected at junction point 31 to the conductor 26 leading to the main S', so that the

key contact *k-1* is normally energized from the main S', as long as the program relay P remains deenergized. Depression of the key K to engage the starting contact 27, as indicated in dotted lines in Fig. 1, thus completes a starting circuit for the motor M, to initiate the transmission of code sequences, as will be hereinafter described.

The program relay P comprises an energizing winding 32 and a main armature 33, carrying 10 the arm 30 that is in engagement with contact 29 when the winding 32 is deenergized. The armature 33 carries a second arm 34 insulated from arm 30, with the arm 34 normally in engagement with stationary contacts 35 and 36, 15 that are under a certain degree of flexure, as indicated. These contacts 35 and 36 are connected by conductors 37 and 38, in parallel with a pair of normally closed contacts 39 and 40, with the flexible contact 39 bearing at its end 20 on an extension 41 movable with the arm 17, although insulated therefrom.

One terminal of the winding 32 of the program relay P is connected to the supply main S', while the other terminal thereof is connected 25 through a resistance 42 to one of a pair of normally open program contacts 43. As will be hereinafter described, these program contacts 43 are adapted to be momentarily closed at a predetermined time, under the control of a suitable clock-operated device, not shown, or they can be closed 30 manually, or by any other means. The other program contact 43 is connected to the contact 39 which, as previously pointed out, is normally in engagement with contact 40 that is in turn 35 connected by conductor 44 to the supply main S.

A pull-in circuit for the relay winding 32 is provided around the resistance 42 between the junction points 45 and 46, which circuit includes 40 a pair of relatively movable contacts 47 and 48, one of which is mounted on the arm 22 cooperating with the motor control cam 20, although insulated therefrom and also from contact 23. With the end of the arm 22 in the cam notch 21, the depressed arm maintains the contacts 47 and 45 48 in engagement, but as soon as the cam 20 starts to turn, the arm 22 rides up on the periphery of the cam to move contact 48 away from stationary contact 47, while at the same 50 time closing contacts 23 and 24.

The program relay P provides a second or auxiliary armature 49 of considerably less weight than the main armature 33, so that the armature 49 will pull in when the winding 32 is traversed by a current such as will flow with the winding 55 in circuit with the resistance 42. The strength of the current required to pull in the armature 49, while not sufficient to cause the main armature 33 to pull in, is nevertheless sufficient to hold in the main armature 33, assuming that the latter has previously been pulled in by current 60 traversing the shunt circuit around the resistance 42, through contacts 47 and 48. The auxiliary armature 49 carries a bridging member 50 insulated therefrom and adapted to engage a pair of spaced stationary contacts 51 when the armature pulls in. Thus contacts 51 are connected in parallel through conductors 52 across the normally open program contacts 43, so as to 65 provide means for short circuiting these contacts whenever the auxiliary armature pulls in.

The contacts 23 and 24 in the holding circuit for the motor M are connected in parallel through conductors 53 to relatively movable contacts 54 and 55 that are normally maintained 70 out of engagement by a pivoted latch 56, having

one end bearing on the contact 55 so as to flex it away from the stationary contact 54. The latch 56 is normally held in the position shown in Fig. 1, by a pivoted armature 57 under control of the winding 58 of a latch relay L. One terminal of the winding 58 of the latch relay is connected to the supply main S, while the other terminal thereof is connected to a stationary contact 59. The contact 59 is normally out of engagement with a movable contact 60, associated with a latch plate 61 bearing on the bevelled end of the key K when the latter is in non-code determining position, as shown in Fig. 1. When the key K is depressed and released, upward movement of the plate 61 before it drops into the key latching notch 62, results in a momentary engagement of contact 60 with contact 59. The latch contact 60 is connected by conductor 63 to a stationary contact 64 normally out of engagement with the movable arm 39 of the program relay, when the winding 32 is deenergized. Therefore, momentary engagement between contacts 59 and 60 resulting from operation of the latch plate 61 by depression of a key K, will have no effect on the latch relay winding 58, unless the program relay P has been previously fully energized to pull in the main armature 33.

The particular construction and mounting of the key K and its associated latching mechanism, forms no part of the present invention, such a latching mechanism being shown, for example, in Burdick Patent No. 1,823,585, issued September 15, 1931, for a Code setting device for signal systems. In order to simplify the showing of the circuits in the system of the present invention, the key K, and its latch plate 61, are shown only diagrammatically in Figs. 1 to 5, inclusive, while the actual construction of these parts is illustrated in the several fragmentary views showing the parts in different positions.

The program relay P also provides a stationary contact 65, normally out of engagement with the arm 39, with the winding 32 deenergized, this contact 65 being connected to the motor circuit conductor 25 at the junction point 66. When the contact 65 is engaged by the arm 39, upon energization of the program relay P, there is provided a second holding circuit for the motor M, as will hereinafter appear from the description of the operation of the system to transmit program impulses.

The system also provides a master relay R, providing a winding 67 having one terminal thereof connected to the supply main S. The other terminal of winding 67 is connected from junction point 68 to one master contact 8 of the code sending mechanism previously described, so that opening and closing of the contacts 8 will result in operation of the master relay R, in accordance with a code sequence, as determined by the key K. The junction point 68 leading from the master relay winding 67, is also connected to the insulated contact 18 carried by the arm 17 bearing on the program disk 15. The cooperating stationary contact 19 is connected by a conductor 69 to one of a pair of spaced stationary contacts 70 adapted to be bridged by the arm 34 of the program relay P, when the winding 32 is fully energized. Since the other relay contact 70 is connected directly to the supply main S', opening and closing of the contacts 18 and 19 by oscillation of the arm 17 as the program disk 15 rotates, is adapted to successively energize and deenergize the master relay winding 67, assum-

ing that the main armature 33 of program relay P has previously been pulled in.

The master relay R provides relatively movable contacts 71, one of which is connected to the supply main S, while the other is connected to the supply main S', in circuit with suitable signals 72, such as bells, horns or lamps. Consequently, successive energizations and deenergizations of the master relay winding 67, will cause operation of the signals 72, either in accordance with a code sequence under the control of the key K and commutating device C, or in accordance with a series of program impulses under the control of the program relay P and program disk 15. Having set forth the construction and function of the various devices entering into the system, the operation thereof will next be described, under the several different conditions previously outlined.

20 (A) *Transmission of code sequences alone*

Upon full depression of the key K, a momentary circuit is established at contact 27, as indicated in dotted lines in Fig. 1 and also in Fig. 10. The motor starting current then flows through the key K and conductor 28, through the engaged contact 29 and arm 39 of the program relay P, which is then in a deenergized condition. As soon as the motor starts, turning of the cam 20, driven from the motor shaft 3 through the reduction gearing 14, closes contacts 23 and 24, which maintain the motor circuit through the conductors 25 and 26 to the supply main S' during one complete revolution of the cam 20, which corresponds to three complete revolutions of the motor shaft, as illustrated.

The motor starting circuit through the contact 27, is immediately broken upon release of the key K, which becomes latched in code determining position, as indicated in Figs. 2 and 11, with the end of the key out of engagement with contact 27. The momentary closure of contacts 59 and 60 by the latch plate 61, which results from depression and release of the key K, has no effect on the latch relay winding 58, owing to the fact that the contact 64 is out of engagement with the arm 39 of the then deenergized program relay P.

With the key K in code determining position, as shown in Fig. 2, certain of the key contacts, namely k-3 and k-4, become energized from the supply main S' through the common contact k-1, the particular selection of contacts shown being chosen to cause transmission of a code signal sequence corresponding to the numeral "twelve." Corresponding contacts c-1, c-3 and c-4 of the commutating device C, will also be energized from the supply main S', through the connections between the code determining device and these contacts. As the motor shaft 3 rotates, the connected arms 2 and 4 successively bear upon the contacts c-1, c-2, etc. and contacts 5, so that the ring 6 becomes connected to the supply main S' at intervals determined by the arrangement of the then energized key-actuated contacts k-1, k-3 and k-4.

Shortly after the arm 2 rides up on the first contact c-1, the arm 10a also rides up on the first projection 12 on the disk 11, so as to close the circuit between the master contact members 8. When this occurs, the circuit through the winding 67 of the master relay R is completed, thereby energizing the signals 72 to transmit the first impulse of the code sequence. Since the projections 12 on the disk 11 have a smaller angular

span than the ring contacts, the circuit of the winding 67 is broken at the master contacts 8, before the arms 2 and 4 leave their contacts; as a result, no arcing can take place at the ring contacts.

Continued rotation of the arm 2 to engage contacts c-2, c-3 and c-4, will result in the transmission of a second and a third signal impulse, with a pause between the first and second impulses, due to the non-energized contact c-2, to correspond to the signal sequence "twelve". This signal sequence will be repeated as the shaft 3 makes a second and third revolution, assuming that the ratio of the gearing 14 between the shafts 3 and 13 is three to one. As the shaft 3 completes its third revolution, the arm 22 enters the notch 21 on the periphery of the control cam 20, thereby separating contact 23 from contact 24, to break the motor circuit. The parts of the system thereupon come to rest in the position of Fig. 1, even though the key K remains in its latched position. The particular latching arrangement for the key K is shown merely for illustrative purposes, since the invention contemplates the use of any desired type of code determining device providing means for setting up different contact combinations in cooperation with the commutating device C.

During the transmission of signal impulses in accordance with the selected code sequence, as described above, the rotation of the program disk 15, causes the contacts 18 and 19 to be successively closed and opened as the arm 17 bears on the projections 16. Such operation of the contacts 18 and 19, however, has no effect on the master relay winding 67, since the contact 19 connected to the program relay contact 70 is disconnected from the supply main S', while the program relay P remains deenergized. Therefore, the system continually remains in a condition wherein closure of the program contacts 43 will cause transmission of program impulses, as will next be described.

(B) *Transmission of program impulses alone*

Let it now be assumed that with the system in the non-operating condition of Fig. 1, program contacts 43 are momentarily closed, as by means of a suitable clock-operated device, not shown. When this occurs, a circuit is established for the program relay winding 32 from the supply main S through conductor 44, then closed contacts 40 and 39, to the junction point 46. From this point, the circuit is through the closed contacts 47 and 48 to junction 45 and the lower terminal of the winding 32, thereby shunting out the resistance 42 and causing sufficient energization of the winding 32, as to pull in both the armatures 33 and 49. As the auxiliary armature 49 pulls in, bridging member 50 engages contacts 51, thereby establishing a holding circuit around the program contacts 43, so that the subsequent opening of these contacts has no effect on the continued energization of winding 32.

Pulling in of the main armature 33, as shown in Fig. 3, causes the relay arm 30 to disengage contact 29, thereby entirely disconnecting key K of the code determining device from the supply main S'. This is followed by engagement of arm 30 with the stationary contact 65, to establish a circuit for the motor M from the junction point 66 of motor conductor 25 to main S'. Turning of the control cam 20 by the motor shaft 3, thereupon causes the arm 22 to ride out of the cam notch 21, so as to disengage contacts 47 and 48

while engaging contacts 23 and 24, to establish a parallel holding circuit for the motor, the purpose of which will hereinafter appear. Upon separation of the contacts 47 and 48, the shunt circuit around the resistance 42 is broken, thereby reducing the current flowing through the program relay winding 32, but not sufficiently to permit the main armature 33 to drop back.

Pulling in of the main armature 33 also causes the arm 34 to leave contacts 35 and 36 and engage the contacts 70, thereby establishing a circuit from the supply main S' to the stationary contact 19. Subsequently, rotation of the program disk 15 from the position of Fig. 1 to the position of Fig. 3, turns the arm 17 as it engages a projection 16, to engage the contact 18 with the contact 19. When this occurs, a circuit is established for the master relay winding 67 from the junction point 68, thereby transmitting the first impulse of the program signal sequence. As previously pointed out, the program disk projections 16 are closely spaced, so that continued rotation of the disk 15 causes a series of evenly spaced signal impulses to be given in rapid succession and without code significance. The number of program signal impulses will depend upon the number of projections 16 on the disk 15, and as shown, the impulses are continued over a period greater than that required for sounding one round of code impulses.

As the program disk 15 nears the completion of one revolution from the position of Fig. 1, the arm 17 drops into a notch 15a on the periphery of the disk, thereby opening the circuit of the program relay winding 32 as the contacts 39 and 40 separate, as indicated in dotted lines in Fig. 4. When this occurs, both armatures 33 and 49 fall back, thereby interrupting the motor circuit at the contact 65 and opening the previously bridged contacts 51 in parallel with the then open program contacts 43. The motor, however, continues to operate, due to the fact that the motor-holding circuit beyond the junction point 66 in conductor 25, is still closed through contacts 23 and 24. Consequently, the disk 15 turns through a few more degrees to bring it to the position of Fig. 1, whereupon the motor stops as the arm 22 enters the notch 21 to cause separation of contacts 23 and 24. The resulting reengagement between contacts 39 and 40 has no effect on the program relay winding 32, since both pairs of contacts 43 and 51 are then open, and there is no way in which current can flow to the winding 32. All parts of the system are therefore restored to the condition of Fig. 1 at the completion of the transmission of the series of program impulses by the signals 12.

Having described the operation of the system to cause the transmission of code sequences alone, as well as the transmission of a series of program impulses alone, there will next be described the operation of the system, wherein the transmission of code sequences in response to initial actuation of a key, is automatically followed by transmission of program impulses, in response to closure of the program contacts at any time during the transmission of code sequences.

(C) *Transmission of code impulses followed by program impulses*

Let it now be assumed that during the transmission of code signal sequences in response to operation of a key K, as previously described

with reference to Fig. 2, the program contacts 43 are closed momentarily. When this occurs, current from the supply main S, is unable to flow to the program relay winding 32, through the shunt circuit around the resistance 42, owing to the fact that the contacts 47 and 48 are then held separated by the arm 22 riding on the periphery of the motor control cam 20. Therefore, the current traversing the winding 32 is so limited by the resistance 42, that only the auxiliary armature 49 pulls in to close the contacts 51 and establish a holding circuit for the partially energized winding 32, around the program contacts 43, when the latter are opened. Since only the auxiliary armature 49 has pulled in, as shown in Fig. 4, the program relay arm 30 remains down to maintain the connection of the code sending mechanism to the supply main S' through the contact 29. Since the other program relay arm 34 also remains down, the contacts 18 and 19 under the control of the program disk 15, remain disconnected from the supply main S', so that transmission of the code impulses remains undisturbed, in spite of the closure of program contacts 43 and pulling in of the auxiliary armature 49. It is also to be noted that while the program relay arm 34 remains down, a shunt circuit is maintained around the then closed contacts 39 and 40, by reason of engagement of the arm 34 with stationary contacts 35 and 36.

As the program disk 15 near the completion of one revolution, coincidentally with transmission of the code sequences, the arm 17 drops into the notch 15a so as to cause separation of the contacts 39 and 40. The opening of these contacts, however, does not permit the auxiliary armature 49 to drop, since the circuit to the program relay winding 32 through the resistance 42 is then maintained through the conductors 37 and 38 and the contacts 35 and 36, then bridged by the arm 34.

Consequently, when the motor M comes to rest at the end of the transmission of three complete rounds of code sequences, reclosure of contacts 47 and 48 as the arm 22 enters the notch 21, reestablishes the shunt circuit around the resistance 42 to cause full energization of the program relay winding 32. The resulting pull up of main armature 33 thereupon restarts the motor M as contact 65 is engaged by relay arm 30 that is always connected to the supply main S', whereupon there follows the transmission of a complete series of program impulses, as previously described with reference to Fig. 3. In other words, closure of the program contacts 43 at any time during the transmission of code sequences, results in placing the system in condition to automatically proceed with the transmission of a complete series of program impulses as soon as the motor comes to rest at the completion of the last round of code sequences. It is to be noted that as the program relay arms 30 and 34 pull up, the initially flexed contacts 35 and 36 follow the arm 34, until after the arm 30 engages motor starting contact 65, and the program disk 15 has moved arm 17 out of the notch 15a to close contacts 39 and 40. That is to say, the following contacts 35 and 36 are not disengaged from the upwardly moving relay arm 34 until after the motor M has been restarted to initiate a complete series of program impulses.

As previously pointed out, the system also contemplates the provision of means whereby the

transmission of program impulses in response to closure of the program contacts 43, is automatically followed by transmission of three complete rounds of code sequences in response to actuation of a code determining key at any time during the transmission of program impulses, and there will next be described the operation of the system on this basis.

(D) *Transmission of program impulses followed by code impulses*

Should the switchboard operator receive an incoming call during the transmission of program impulses, as described with reference to Fig. 3, and desire to broadcast through the system a given code number for the person wanted, the operator immediately pushes in the selected code key K, without waiting for the transmission of the program impulses to be completed.

When the key K is pressed all the way in, as shown in dotted lines in Fig. 1, engagement of the motor starting contact 27 by the end of the key, has no effect on the motor M, since at that time the stationary contact 29 of program relay P is disconnected from the supply main S', by reason of the main armature 33 being held up during the transmission of program impulses, see Fig. 3. However, as the key K is pressed in and released, the contact 60 is momentarily engaged with the contact 59 as the latch plate 61 is moved upwardly to its extreme position, before dropping into the notch 62 to latch the key in code determining position. Since the stationary contact 64 of the program relay is at that moment connected to the supply main S' through the then raised relay arm 30, engagement between contacts 59 and 60 serves to energize the winding 58 of the latch relay L, as shown in Figs. 5 and 9.

Energization of winding 58 pulls in the armature 57, thereby permitting the pivoted latch 56 to turn in a counterclockwise direction, as indicated, to cause engagement between contacts 54 and 55, and thereby provide a shunt circuit in parallel with the then closed motor-holding contacts 23 and 24. In other words, closure of contacts 54 and 55 places the system in condition for restarting the motor M, although at that moment, actuation of the code determining key K has no effect, due to the disconnection of the contact 29 from the supply main S', during the transmission of program impulses.

Continued rotation of the program disk 15, following the depression and latching-in of a key K, as described above, carries on transmission of the program impulses until near the completion of one revolution of the disk 15, whereupon the arm 17 drops into the notch 15a to separate contacts 39 and 40. While the resulting deenergization of the program relay winding 32 permits the main armature 33 to drop, connection of the contact 29 to the supply main S' has no immediate effect, since at that moment, the arm 2 is bearing on the periphery of the ring 1 and is therefore insulated from the energized commutating contacts c-1, c-2, etc.

As previously pointed out, the angular relation between the notches 15a and 21 is such that the arm 22 enters the notch 21 very shortly after opening of the contacts 18 and 19 has deenergized the program relay winding 32 at the completion of the transmission of a complete series of program impulses. When this occurs, the previously closed holding circuit for the motor M is broken at the contacts 23 and 24, but the mo-

tor does not stop, owing to the previous closure of contacts 54 and 55 to provide a shunt circuit around the contacts 23 and 24. Therefore, the continued operation of the motor M results in the immediate transmission of code sequences, as determined by the circuits established through the depressed key K. Obviously, the motor M will continue to operate through three complete revolutions of the shaft 3, due to reclosure of the contacts 23 and 24.

After the motor M has turned the cam 29 sufficiently to reengage the holding contacts 23 and 24, a pin 73 on the disk 15, engages the pivoted latch 56. It is evident from a consideration of Fig. 5, that when the latch 56 turns into position to permit closure of contacts 54 and 55, a beveled surface 56a on the latch will be disposed in the path of the pin 73. Therefore, continued rotation of the disk 15, through a few degrees, following the automatic initiation of code sequences, as described above, will result in turning the latch back to the position of Fig. 1, to separate the contacts 54 and 55, as shown in Fig. 6. Therefore, the system is restored to the condition of Fig. 1, upon the completion of the transmission of code sequences, and when the motor M comes to rest, with the arm 22 in the notch 21 of the motor-controlled cam.

From the foregoing, it is apparent that the system of the present invention works on an automatically non-interfering and succession operation basis, entirely irrespective of whether a code determining key or program device operates first. Therefore, when either a code determining key is depressed, or the program contacts are closed, while the system is operating, a complete series of program impulses will be followed by a complete cycle of code sequences, or vice versa.

I claim:

1. A signal sending system, comprising in combination, a code determining device, means for transmitting code impulses under the control of a manually operable code determining element of said device, means for transmitting a series of impulses with a different significance under the control of an auxiliary contact making device, a common driving means for said impulse transmitting means and connections between said impulse transmitting means for controlling the operation of said driving means and causing the transmission of one or more complete rounds of code impulses in response to initial operation of said code determining element, while preventing transmission of series impulses in response to operation of said auxiliary contact making device during the transmission of code impulses, with said connections between said transmitting means also serving to automatically cause continued operation of said driving means and the transmission of said series impulses upon the completion of the last round of code impulses.

2. A signal sending system, comprising in combination, a code determining device, means for transmitting code impulses under the control of a manually operable code determining element of said device, means for transmitting a series of impulses with a different significance under the control of an auxiliary contact making device, a common driving means for said impulse transmitting means and connections between said impulse transmitting means for controlling the operation of said driving means and causing the transmission of a series of impulses in response to operation of said auxiliary device, while pre-

venting transmission of code impulses in response to actuation of said determining element at any time during the transmission of said series impulses, with said connections between the impulse transmitting means also serving to automatically cause continued operation of said driving means and the transmission of code impulses immediately following the completion of the transmission of said series impulses.

3. In a signal sending system, the combination with a code determining device, a device for transmitting impulses according to a selected code of said determining device, a device for transmitting a series of impulses with a significance different from that of the selected code, and a common driving means for both of said impulse transmitting devices, of means for independently initiating operation of said driving means for transmission of either type of impulse over a predetermined period, and means for sustaining operation of said driving means while causing either type of impulse to automatically follow the other, irrespective of which type of impulse is initially transmitted.

4. In a signal sending system, the combination with a code determining device, a device for transmitting impulses according to a selected code of said determining device, a device for transmitting a series of impulses with a significance different from that of the selected code, and a common driving means for both of said impulse transmitting devices, of means for independently initiating operation of said driving means for transmission of either type of impulse over a predetermined period, and means for automatically preventing interference between transmission of the two types of impulses, irrespective of continued operation of said driving means and which type of impulse is initially transmitted.

5. In a signal sending system, the combination with a code determining device, a device for transmitting impulses according to a selected code of said determining device, a device for transmitting a series of impulses with a significance different from that of the selected code, and a common driving means for both of said impulse transmitting devices, of means for initiating operation of said driving means for causing transmission of code impulses over a predetermined period in response to initial actuation of said code determining device, automatically followed by transmission of said series impulses in response to subsequent actuation of the series impulse transmitting device, at any time during the transmission of code impulses.

6. In a signal sending system, the combination with a code determining device, a device for transmitting impulses according to a selected code of said determining device, a device for transmitting a series of impulses with a significance different from that of the selected code, and a common driving means for both of said impulse transmitting devices, of means for initiating operation of said driving means for causing transmission of series impulses, over a predetermined period automatically followed by transmission of code impulses in response to subsequent actuation of the code determining device, at any time during the transmission of said series impulses.

7. In a signal sending system, the combination with a code determining device, a device for transmitting impulses according to a selected code of said determining device, a device for transmitting a series of impulses with a signifi-

cance different from that of the selected code, and a common driving means for both of said impulse transmitting devices, of means for initiating operation of said driving member for causing transmission of code impulses over a pre-determined period in response to actuation of said code determining device, means for temporarily withholding transmission of said series impulses in response to actuation of said series transmitting device, at any time during the transmission of code impulses, and means for sustaining operation of said driving means to cause transmission of series impulses immediately following completion of the transmission of code impulses.

8. In a signal sending system, the combination with a code determining device, a device for transmitting impulses according to a selected

5 code of said determining device, a device for transmitting a series of impulses with a significance different from that of the selected code, and a common driving means for both of said impulse transmitting devices, of means for initiating operation of said driving means for transmitting a series of impulses over a predetermined period in response to actuation of said series transmitting device, means for temporarily withholding transmission of code impulses in response to actuation of said determining member at any time during transmission of said series impulses, and means for sustaining operation of said driving means to cause transmission of code impulses immediately following the completion of the transmission of series impulses.
